UNITED STATES PATENT OFFICE.

CHARLES R. HARRIS, OF WILLIAMSPORT, PENNSYLVANIA.

DESIGN FOR A BODY FOR AUTOMOBILES.

SPECIFICATION forming part of Design No. 32,198, dated February 6, 1900.

Application filed January 3, 1900. Serial No. 295. Term of patent 14 years.

To all whom it may concern:

Be it known that I, CHARLES R. HARRIS, a citizen of the United States, residing at Williamsport, in the county of Lycoming and State of Pennsylvania, have invented and produced a new and original Design for a Body for Automobiles, of which the following is a specification, reference being had to the accompanying drawings, forming a part thereof.

10 In the accompanying drawings, Figure 1 is a view in perspective illustrating my design, and Fig. 2 is a view in section of the same.

The leading feature of my design consists in a body for automobiles whose sides have a continuous unbroken curved outline.

15 A represents the dashboard, and B the sides of the body for automobiles. The edge of each side comprises a continuous tubular portion 1. Starting at the point 2 at the base of

the dashboard A the tubular edge 1 curves 20 gradually downward and rearward to a point about midway the body, as shown at 3, then upwardly to a point 4, so as to mark approximately a semicircle. From the point 4 the tubular edge curves downwardly into an approximately vertical portion 5. At the lower end of the portion 5 the edge is curved rather abruptly, as at 6, and then extends upwardly and merges into the dashboard A, as shown at 7.

30 What I claim is—

The design for a body for an automobile shown and described.

CHAS. R. HARRIS.
